UNITED STATES PATENT OFFICE.

JAMES A. CHARTER, OF CHICAGO, ILLINOIS, ASSIGNOR TO AUSTIN MANUFACTURING COMPANY, OF CHICAGO, ILLINOIS, A CORPORATION OF ILLINOIS.

ELECTRIC IGNITER FOR GAS-ENGINES.

938,123.

Specification of Letters Patent. Patented Oct. 26, 1909.

Application filed July 28, 1908. Serial No. 445,783.

To all whom it may concern:

Be it known that I, JAMES A. CHARTER, a citizen of the United States, residing at Chicago, in the county of Cook and State of Illinois, have invented certain new and useful Improvements in Electric Igniters for Gas-Engines, of which the following is a specification.

This invention relates to the art of explosive engines, and has reference more particularly to a new and improved ignition mechanism for firing explosive charges admitted to the engine cylinder.

My present improvements are embodied in that type of ignition mechanism employing relatively fixed and movable electrodes in the explosion chamber of the engine, a magneto of the oscillating armature type, and electric connections between said magneto and electrodes.

One of the principal objects of the invention is to provide a simple mechanism whereby the ignition can be adjusted or timed properly to the engine cycle while the engine is in motion. This is a very desirable feature, since with different fuels, different rates of speed, etc., the point of explosion must be varied in relation to the position of the crank at the time the explosion is to be produced.

Another object of the invention is to provide an igniter mechanism which will permit the positive starting of the engine from a stand-still, using the current from the magneto which is regularly used when the engine is running, and preventing any danger of the engine reversing or starting to run backward when starting up.

Other objects and advantages attained by the invention will be apparent from the following description.

My invention will be readily understood when considered in connection with the accompanying drawings showing one practical mechanical embodiment thereof, in which,—

Figure 1 is an end elevational view of an engine cylinder and its side shaft showing my improved igniter mechanism applied thereto. Fig. 2 is a top plan view of the parts shown in Fig. 1. Fig. 3 is a detail elevation of the adjusting mechanism for the magneto trip whereby the time of sparking is varied relatively to the piston stroke. Fig. 4 is a cross-sectional detail, enlarged, on the line 4—4 of Fig. 3.

Referring to the drawings, 5 designates a portion of the engine cylinder, and 6 the cylinder head secured to the forward end thereof, said head containing the usual explosion chamber. Secured within and centrally of the end wall of the head 6 is an igniter casting 7 which carries a fixed electrode 8 and a movable electrode 9, the shaft of which latter is journaled in the casting 7 and at its outer end carries a short depending arm 10 having a laterally projecting pin 11; a spring 12 connected to said arm normally tending to rock the shaft of the movable electrode in a direction to maintain contact between the electrodes. The fixed electrode 8 is suitably insulated, as usual, and has an electrical connection with the magneto through a wire indicated at 13.

The magneto herein shown and designated as an entirety by 14 is known as the oscillating type, the armature being of such a construction and shape, and so positioned within the pole-pieces of the magnets that it is necessary to turn the armature only approximately thirty degrees to bring it into contact magnetically with the poles, and when it is released from the operating device, hereinafter described, the armature is drawn back into its neutral or central position by means of two strong springs 15 attached to a cross-arm 16 fast on the shaft of the oscillating armature. This being a standard make of magneto, no very detailed description thereof is necessary to a full understanding of the present invention.

Referring now more particularly to those features wherein my present improvement resides, 17 designates a pendulum arm that depends from the armature shaft. Pivotally connected to the pendulum 17 near its lower end is a connecting rod 18, the inner end of which is screwed into a slotted link 19 formed with a closed outer end 20, the slot of this link 19 engaging the pin 11 carried by the igniter arm 10.

The pendulum 17 is actuated in a manner to effect a quick separation of the electrodes 8 and 9 by the following mechanism. On the side shaft 21 of the engine is mounted a disk 22, said disk having on one side a laterally projecting boss or hub 23. This boss or hub has a radial slot 23^a engaged by a pin 23^b projecting from the shaft for the purpose of confining the disk against movement endwise of the shaft. The disk 22 is mount-

ed beneath the armature of the magneto and in such position that the depending end of the pendulum arm 17 overlaps the forward face of the disk. On the same face of the disk 22 is mounted a pivoted trip 24, the upwardly projecting ends of which are adapted to travel in a circular path across which the lower end of the pendulum arm 17 is projected. The trip 24 has a tail-piece 24^a normally held in engagement with the periphery of the hub 23 by a light spring 25.

From the foregoing it will be seen that when the disk 22 revolves in a contra-clockwise direction, the trip 24, engaging the pendulum 17, will oscillate the armature the required thirty degrees, more or less, to suit the conditions of the magneto; and, as soon as the catch has cleared the lower end of the pendulum arm, the springs 15 instantly return the armature to a neutral position, thereby generating the electric current through the wire 13, fixed electrode 8, movable electrode 9, and metallic engine frame, back to the generator, which current is interrupted or broken at the electrodes at the instant of its highest efficiency by the rebound of the pendulum arm acting through the rod 18 and link 19, the closed end 20 of the latter striking the pin 11 and thus rocking the movable electrode 9 away from the fixed electrode 8.

The time of sparking, relatively to the piston stroke is, in accordance with my invention, varied by varying the time, relatively to the stroke, at which the trip 24 engages the pendulum arm; and this is effected by an angular operation of the disk 22 on the side shaft 21. Referring to the means for effecting this angular adjustment 40 of the disk 22, and considering more particularly Figs. 2 and 3, it will be seen that behind the disk 22 on the shaft 21 is mounted an annularly grooved collar 26, said collar being provided with a key 27 slidable in a longitudinal key-way 28 in the shaft 21. The outer end of this key is turned up, as shown at 27^a, forming a projection which is fitted into an oblique groove 29 formed in the inner periphery of the disk 22 and its hub 23. From this it will be seen that a longitudinal sliding movement of the collar 26 on the shaft 21 will impart a partial rotation to the disk 22 in one direction or the other, according to the direction of movement of the collar 26 along the shaft 21, the disk 22 being held against endwise movement on the shaft. The means which I provide for effecting this adjustment of the disk 22 while the engine is running are perhaps best shown in the detail view, Fig. 3, wherein 30 designates a manually operable lever pivoted at 31 to a fixed member of the frame and having a forked lower end embracing the annular groove of the collar 26. The longer arm of the lever plays over

a quadrant plate 32 provided with a series of holes 33, with any one of which a spring catch 34 carried by the lever 30 may be engaged to hold the collar 26 in any adjusted position and thus, through the key 27 and its upturned end, secure the trip-carrying disk 22 in any angularly adjusted position.

Briefly describing the operation of the mechanism as a whole, the said shaft 21 is rotated continuously from the crank shaft 75 of the engine, and at a fixed relation thereto, in a contra-clockwise direction. The contact of the trip 24 with the pendulum arm 17, therefore, tilts the pendulum toward the left, or in a direction toward the igniter. 80 By means of the slotted link 19 the pendulum can travel thirty degrees, more or less, as required by the magneto, without contacting with the pin 11 carried by the actuating arm 10 of the movable electrode; but 85 when the pendulum is released and flies back into its central or neutral position, under the influence of springs 15, it carries with it the rod 18 and link 19, which have been so adjusted by virtue of their screw-threaded 90 connection that a slight rebound past the central position of the pendulum causes the outer or closed end 20 of the link 19 to strike the pin 11, and by this contact the electrode shaft is slightly turned, carrying the movable electrode away from the face of the fixed electrode, thus opening the electric circuit and permitting the discharging of the electric current produced by the magneto to jump and form an arc or a spark between 100 the open points of the movable and fixed electrodes.

By manually adjusting the lever 30, the angular position of the trip 24 relatively to the shaft 21 is varied, so as to actuate 105 the magneto and separate the electrodes at the desired or proper point in the cycle. In practice, when it is desired to start the engine it is simply necessary to charge the cylinder with an explosive mixture (which in 110 this case I accomplish by connecting a small hand-operated charging pump to the cylinder through a suitable opening provided in the cylinder head, and supplying the mixture between the latter and the piston. The 115 crank of the engine is then set on the explosion position, just enough above the center to allow the pressure set up or caused by the hand pump to start the piston on its out stroke. At this time the disk 22 has 120 been so adjusted that the trip 24 will not release the armature of the magneto from its swung position of approximately thirty degrees out of line until the piston has traveled 125 slightly forward and revolved the shaft 21 and caused the disk 22 also to revolve, allowing the trip 24 to pass under the pendulum 17. Then the springs 15 reset the armature, as above described, and produce the spark. The engine then is given sufficient force to 130

store up energy in the fly wheels and cause the rotation of the shaft, drawing in a second charge into the cylinder through the regular mixer provided with the engine. This new mixture is then compressed and exploded in the same manner, and the engine is allowed to run for a few revolutions until it builds up in speed. Then, by releasing the spring catch 34 on the lever 30, the collar 10 26 controlling the disk 22 which operates the magneto, is advanced in relation to the shaft 21, and the explosions are produced at an earlier point in the cycle of the engine, preferably below the dead center. This point can 15 be varied to a considerable extent on either side of the dead center to suit the conditions and speed of the engine and fuel used, and without necessitating the stopping of the engine.

20 I claim:

1. In an igniter mechanism for gas engines, the combination with a pair of separable electrodes, and a magneto for supplying current thereto, said magneto having 25 an oscillatory armature, of a pendulum arm fast on said armature, a link connecting said pendulum arm and movable electrodes through a pin-and-slot connection permitting movement of said link in one direction without actuating said electrode, a spring opposing the turning movement of said armature and, when tensioned and released, effecting a return swing of said pendulum arm past the neutral position of said 30 35 armature whereby to separate said electrodes, a rotary shaft adjacent to said magneto, a disk rotatable but confined against endwise movement on said shaft, a trip carried by said disk and adapted to engage and swing 40 said pendulum arm thereby tensioning said spring, and hand-operated means operable while the engine is running to shift said disk in either direction around said shaft, substantially as described.

2. In an igniter mechanism for gas engines, the combination with a pair of normally closed separable electrodes, and spring-actuated mechanism for separating said electrodes, of a rotary shaft, a disk on said shaft having a hub, a trip pivoted on the face of said disk and having a tail-piece, a spring normally holding said trip with its nose projected beyond the periphery of the disk and its tail-piece in contact with said hub, whereby said trip is adapted to 55 contact with and tension and then release said electrode-separating mechanism when traveling in a forward direction, but is compressible when traveling backward, a manually operable lever, means actuated by said lever for adjusting said disk in either direction around said shaft, and means for locking said lever in set position, substantially 60 as described.

3. In an igniter mechanism for gas engines, the combination with a pair of normally closed separable electrodes, a magneto for supplying current thereto, and a spring-actuated mechanism for actuating the armature of said magneto and separating said 70 electrodes, of a rotary shaft beneath said magneto, a disk on said shaft, a spring-projected trip mounted on said disk adapted to contact with and tension and then release said armature-actuating and electrode-separating mechanism, a key slidably mounted on said shaft for shifting said disk around said shaft, a pivoted hand-lever pivotally connected to said key, a quadrant plate provided with a plurality of holes, and a spring 75 catch carried by said lever and adapted to engage any one of said series of holes to secure said lever in set position, substantially 80 as described.

JAMES A. CHARTER.
